OVEREDGE SEWING MACHINE

Nicholaus Knaus, Cranford, N. J., assignor to The
Singer Manufacturing Company, Elizabeth,
N. J., a corporation of New Jersey

Application September 10, 1946, Serial No. 695,985

21 Claims. (Cl. 112—162)

1

This invention relates to overedge sewing machines and more particularly to means embodied therein for hem-folding the marginal portions of both flat and tubular workpieces and for so presenting the folded workpieces to the trimming and stitch-forming mechanisms that the projecting edge portion of each workpiece is trimmed off substantially in line with the fold and the hem is secured to the body material by a blind-stitch overedge seam.

A primary object of the invention is to provide an improved mounting for the hem-folder whereby the machine will be devoid of certain obstructions which, in prior machines, have interfered with the free passage of the work and have caused snarling of the trimmed off portion of the work and, when hemming tubular work, of the thread-chain which is connected to the work at the beginning end of the seam.

Another object of the invention is to provide an improved hem-folder which may be used for folding either tubular or flat work.

Another object is to provide a throw-out hem-folder having readily releasable latch means for holding the hem-folder in its operative position.

Still another object is to provide an improved mounting for a hem-folder which affords means for adjusting the hem-folder relative to the stitching point in a plurality of transverse directions.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings

Fig. 1 is a front elevation, partly in section, of a portion of an overedge sewing machine showing it fitted with one form of improved hem-folder adapted for hem-folding both flat and tubular work-pieces.

Fig. 2 is a plan view of that portion of the machine illustrated in Fig. 1.

Fig. 3 is a left end view thereof.

Fig. 4 is a transverse vertical section taken substantially on the line 4—4 of Fig. 2.

Fig. 5 is a detail horizontal section taken substantially on the line 5—5 of Fig. 1.

Fig. 6 is a detail horizontal section taken on the line 6—6 of Fig. 1.

Fig. 7 is a detail vertical sectional view taken on the line 7—7 of Fig. 4.

Fig. 8 is a detail horizontal section taken on the line 8—8 of Fig. 1.

Fig. 9 is a detail vertical section taken on the line 9—9 of Fig. 2.

2

Fig. 10 is a disassembled perspective view of an edge-guide hereinafter to be described.

Fig. 11 is a disassembled perspective view of the supporting means for the hem-folder shown in Fig. 1.

Fig. 12 is a perspective view of a modified form of hemmer particularly adapted for hem-folding flat, or so-called "open end," workpieces.

Fig. 13 is a perspective view of a second modified form of hemmer particularly adapted for hem-folding tubular workpieces.

Referring more specifically to the drawings, the invention is shown as embodied in an overedge sewing machine of the type disclosed in United States patent of N. Knaus, No. 2,238,796, Apr. 15, 1941.

The machine has a main frame F comprising a base portion 1 and an upstanding portion 2. The base portion carries a horizontally disposed work-supporting plate 3 and a throat-plate 4 provided with slots through which operates serrated feed-dogs forming a part of work-feeding mechanism hereinafter referred to. The main frame also supports overedge stitch-forming mechanism comprising a reciprocating curved needle 5, an under or needle-loop-taking thread-carrying looper 6 and an overedge looper or loop-spreader 7 which cooperates with the needle 5 and looper 6 in the formation of overedge stitches. The machine also includes a conventional work-feeding mechanism designated generally as f and a cooperating presser-device for advancing the work to and beyond the stitch-forming mechanism. The presser-device comprises a horizontally disposed spring-depressed presser-bar 8 pivoted, at its rear end, to the machine frame and carrying, at its forward end, a presser-foot 9 which overlies the serrated feed-dogs which form a part of the work-feeding mechanism.

The machine further includes a trimming mechanism adapted to trim the work at one side of the line of seam formation. The trimming mechanism includes a vibratory trimmer-bar 10 actuated from the main shaft of the machine and carrying, at its forward end, a movable trimmer-blade 11, which cooperates with a stationary trimmer-blade 12 carried by the base portion 1 of the machine frame. Inasmuch as the specific constructions of the stitch forming, work-feeding and work-trimming mechanisms are shown in the above mentioned patent and form no part of the present invention, further illustration and description thereof is deemed unnecessary.

As hereinbefore indicated, this invention relates primarily to improved means, embodied in a machine of the type above described, for so presenting the work to the stitch-forming mechanism that the marginal portion of the work is folded into flattened S-shape, with the upper-

60

most portion thereof trimmed substantially in vertical alignment with the lowermost fold. The needle thereupon penetrates the upper ply, adjacent the trimmed edge thereof, and passes through the underlying fold, entering and emerging from the same side of the work. The loopers cooperate with the needle to form an overedge seam which covers the trimmed edge and secures the hem to the body of fabric by so-called "blind stitching."

When hemming tubular work the stitching may commence at any point and proceed around the work until the point of beginning has again reached the stitching point. In positioning tubular work in the machine, preparatory to the beginning of the hemming operation, it is customary to raise the presser-foot and to move the work back and forth by hand, in the line of seam formation, through the hem-folder and beneath the presser-foot until the work is properly folded and properly positioned relative to the trimming and stitch-forming mechanisms; after which the presser-foot is lowered and the sewing begun. For this purpose it is desirable that the hem-folder be maintained in its working position.

In preparing to hem flat work, in which the hemming starts at one edge of the work and progresses thereacross to the opposite edge thereof, it is customary to swing the hem-folder upwardly and out of working position; then to hem-fold the marginal portion of the work manually and insert it between the presser-foot and the underlying cloth-plate and feed-dog, and thereafter to swing the hem-folder downwardly into operative position with the blade of the hem-folder inserted between the lower two plies of the folded hem.

When hemming either tubular or flat work, it is desirable that the hem-folder be permitted to have a slight rising and falling movement in its operative position. This movement permits the folder to adapt itself to variations in the thickness of the work such, for example, as when a cross-seam is passing through the folder, and it also permits the folder to rise and fall with the work under the action of the feed-dog.

The hem-folder disclosed in Figs. 1 to 4 inclusive and 6, 7 and 9 is adapted for hem-folding both flat and tubular work. In other words it is adapted to be swung upwardly and out of working position to facilitate the introduction of flat work and it is also adapted to be locked in its working position which is desirable when introducing and hemming tubular work.

The hem-folder disclosed in Fig. 12, which is adapted primarily for hem-folding flat work-pieces, differs from that shown in Figs. 1 to 4, 6, 7 and 9 in that it has no means for locking it in its working position.

The form illustrated in Fig. 13 is specifically designed for hem-folding tubular workpieces and, aside from a slight rising and falling movement under variation in the thickness of the work and the action of the feed-dog, as above described, is permanently maintained in its working position.

All of the three forms of hem-folders are adapted to be removably secured upon a common supporting bracket adjustably mounted in the upstanding portion 2 of the machine frame as hereinafter will be described.

Cooperating with each of the three forms of hem-folders is an edge guide comprising a horizontally disposed block G mounted for horizontal floating movements on a saddle 13 adjustably secured upon support 14 fixed, by a screw 15, to the pedestal portion 16 of the base 1. The saddle 75

13 and the guide block G carried thereby are adjustable bodily lengthwise of the support and transversely of the line of seam formation by an adjusting screw 17. The guide block G is formed with a vertically disposed edge-guiding face 18 which engages and guides that portion of the workpiece which is folded about the work-folding blade of the hem-folder. Pins 19, 20 and 21, carried by and projecting downwardly from the block G, enter, respectively, apertures 19^a and 20^a and 21^a in the saddle 13 thus permitting the block to be moved bodily on the saddle transversely of the guiding face 18 and consequently transversely of the line of seam formation. A coil spring 22, seated in a cavity 23 aligned with the aperture 20^a, has its outer end in engagement with the pin 20 and normally shifts the pin and the guide-block G toward the work-folding blade until the pin 19 engages the wall 19^b of the aperture 19 and the pin 21 engages a wall 24 forming a part of a fixed edge-guiding block 25 secured to the saddle 13 by a screw 26. In addition to its bodily movements transversely of the line of seam formation, the guide block G is adapted to have pivotal movements about the pins 19 and 21. Thus the guide-block is mounted to have pivotal and bodily floating movements in a horizontal plane to facilitate the passage and guidance of a workpiece having an irregular folded edge, such, for example, as one having a cross-seam. A floating edge guide of this general nature is disclosed, in more detail, in the pending United States patent application of N. Knaus and P. Anton, Serial No. 626,936, filed Nov. 6, 1945.

It is to be noted that the edge guide G and the mount therefor are supported by the base 1 below the level of the work, while the hem-folders, which cooperate with the edge-guide, are supported above the level of the work, thereby providing an unobstructed passageway therebetween for the passage of the work. This specific mounting of the parts is an important feature of the present invention.

Each of the three hem-folders disclosed in the drawings is adapted to be attached, selectively, to a vertically disposed bracket 27 secured, at its upper end, by screw 28 to a two-part slide block 29, mounted for horizontal adjustment transversely of the line of seam formation in the head 30^a of a stud 30 adjustably mounted in a bore 31 in the upstanding portion 2 of the frame F. Thus the stud 30, the block 29, bracket 27 and the parts carried thereby may be adjusted parallel to the line of seam formation and held in their various positions of adjustment by means of a set screw 32 threaded into the portion 2 of the frame and bearing upon a flattened surface on the stud 30. The block 29 and the bracket 27 carried thereby may be adjusted on the head 30^a, transversely of the line of seam formation, by an adjusting screw 33 threaded into the head 30^a and having a collar 34 engaging in a notch 29^a in the slide-block 29 (Fig. 8).

As hereinbefore stated, any one of a plurality of hem-folders may be mounted upon the supporting bracket 27. To that end, the bracket is formed with a U-shaped lower end comprising upright arms 27^a and 27^b and a connecting lower wall 27^c. The arms 27^a and 27^b are provided with aligned apertures 35 and 36 which are designed to receive a removable and replaceable pivot pin 37 upon which a carrier for the hem-folding blade of each hem-folder is adapted to be mounted.

Referring first to the hem-folder adapted spe-

cifically for circular work, shown in Fig. 13, the hem-folding blade 38 is shown as having its shank 39 secured, by a screw 40 upon the upper end of a block or carrier 41 pivotally mounted on the pivot pin 37. As hereinbefore stated the hem-folder for tubular work is preferably maintained in its working position but is adapted to have a slight rising and falling movement. This is effected by the pivotal mounting of the carrier 41 together with the engagement of a pin 42, secured in said carrier, with the walls of a vertically disposed slot 43 formed in the free upper end of the arm 27^b of the bracket 27. The pin 42 is somewhat less in diameter than the width of the slot 43 and therefore is free to be moved sidewise therein thus permitting but limiting the turning movement of the block 41 and the hem-folding blade carried thereby.

The construction disclosed in Fig. 12 is designed particularly for hem-folding flat work, in the introduction of which it is desirable to swing the hem-folder upwardly and out of its operative position until the beginning end of the work has been placed beneath the presser-foot and the initial hem-fold has been made manually. In this form a hem-folding blade 44 has its shank 45 secured by bolt 46, to a hinge block 47 pivoted, at 48, to an extension 49^a of a carrier block 49 pivotally mounted, on the pivot pin 37, in the arms 27^a and 27^b of the bracket 27. A stop-plate 50, adjustably secured upon the upper end of the block 49 by a screw 51 passing through a slot 50^a in the plate, has down-turned fingers 52 which engage the straight rear wall 47^a of the hinge block 47 and limit the downward movement of the block 47 and the hem-folder carried thereby. By adjusting the plate lengthwise of the slot 50^a the vertical position of the blade 44 may be varied. The block 49 carries a pin 53 which is located within the slot 43 in the arm 27^b of the bracket 27. This pin is of greater diameter than the pin 42 and does not have any lateral movement in the slot 43; the pivotal movement of the blade 44 being about the axis of the pivot 48.

Likewise the bracket 27 is adapted to have secured thereto the universal hem-folder, shown in Figs. 1 to 4 inclusive and 6, 7 and 9. This folder is designed to handle either flat workpieces or tubular workpieces with equal facility; being locked in operative position when hem-folding tubular workpieces and capable of being swung upwardly out of operative position for the insertion of flat workpieces.

To that end, the device comprises a hem-folding blade 54 having a slotted shank 55 adapted to be secured upon a hinge member 56, by a clamp screw 57 (Fig. 7). Intermediate its ends, the member 56 is pivotally mounted, by a pin 58, on the extended portions 59^a of a carrier block 59 adapted to be pivotally mounted, by the pin 37 hereinbefore mentioned, between the arms 27^a and 27^b of the bracket 27. The block 59 carries a pin 60 having a projecting end which is located in the slot 43 in the arm 27^b for limiting the turning movement of the block and the parts carried thereby. A manually releasable latch device is provided for locking the hinge member 56 and blade 54 to the block 59 so that there is no relative movement therebetween. This latch device comprises a vertically disposed finger-actuated lever 61 the shank of which is located in a slot 62 in the block 59. The lever is pivotally mounted, at its lower end, upon a bolt 63 extending through the portions 59^a of the block and through an aperture 64^a of the lever. A nut 64 threaded on the bolt 63

holds the bolt against endwise displacement. Extending transversely through the latch lever 61 is a pin 65 the projecting portions of which are adapted to enter notches 56^a formed in the hinge member 56, as shown in full lines in Fig. 1, thereby to lock the parts together. The lever 61 is normally urged to turn in a counterclockwise direction, as seen in Figs. 1 and 7, by two coil springs 66 seated in sockets 67 formed in an inverted L-shaped cap plate 68, secured to the block 59 by screw 69. The projecting ends of the springs 66 bear upon the pin 65. The latch lever 61 may be turned clockwise, in opposition to the springs 66 by means of pressure applied manually to a disk-like portion 61^b formed on the upper end of the lever 61. Thus the walls of the notches 56^a in the member 56 and the spring-pressed pin 65 constitute a latch device for holding the hem-folder in its operative position, while the lever 61-61^b constitutes means for releasing the latch to permit the hem-folder to be swung out of its operative position, as indicated in dotted lines in Fig. 1, to facilitate the introduction of flat work. The lower walls of the notches 56^a project beyond the upper walls thereof and constitute abutments which engage the under surface of the pin 65, thereby limiting the counterclockwise movement of the member 56 and the hem-folder carried thereby and aligning the notches 56^a with the pin.

Means also is provided for automatically swinging the hem-folder to the inoperative position illustrated in dotted lines in Fig. 1 when the lever 61 is shifted to release the member 56. This means comprises a plunger, consisting of a pin 70 slidably mounted in a bore 71 in the block 59 and a coil spring 72 bearing upon one end of the pin and urging its opposite end into pressure contact with the member 56 below the pivot 58, as shown in Fig. 7. The spring 72 is held in the bore 71 and maintained under pressure by the downwardly extending portion of the plate 68. Thus when the hem-folder is held in its operative position by the latch 56^a, 65, the hinge member 56 is maintained under spring pressure. Consequently, the instant the latch is released the spring plunger 70 turns the member 56 clockwise (Figs. 1 and 7) sufficiently to shift the notch 56^a out of the path of the pin 65. If the latch is released suddenly, the force of the plunger is released instantaneously and the limited movement of the plunger tends to kick the hem-folder upwardly into its retracted position shown in dotted lines in Fig. 1. However, if the latch is released more gradually the action of the plunger may not be sufficient to shift the hem-folder to its completely retracted position. In that case, the return movement of the latch-releasing lever 61, under the influence of the springs 66 will cause the pin 65 to be brought into pressure contact with cam surfaces 56^b on the member 56 with the result that the pressure of the pin on those surfaces will continue the turning movement of the member 56 until the hem-folder is fully retracted. Regardless of whether the hem-folder is retracted solely by the plunger 70 or by the plunger in combination with the pressure of the pin 65 on the cam surfaces 56^b, the pressure of the pin 65 against the flat surfaces 56^c of the member 56 will hold the hem-folder in its retracted position until it is manually pressed downwardly into operative position.

From the foregoing it will be perceived that the hem-folders are supported from the upper portion of the machine frame above the plane of the work

while the cooperating edge-guide G is supported below that plane.

As illustrated in Fig. 1 a workpiece w passes over the work-supporting plate 3 and has its marginal portion folded into flattened S-shape and passed to the trimming and stitch-forming mechanisms by the combined actions of the hem-folder and the edge-guide. That portion of the workpiece which extends to the right beyond the lower fold t is trimmed off by the trimming mechanism as is also the thread-chain which is formed preparatory to the sewing of a tubular article.

The specific mounting of the edge-guide and the hem-folder affords an unobstructed passageway therebetween and thus there is nothing to obstruct the free passage of the thread chain and trimmed off marginal portion. To facilitate gravitational discharge of the trimmed off parts of the workpiece, the upper surface of the guide block G is bevelled laterally as indicated at g and longitudinally as indicated at g'. Cooperating with the bevels g and g', in removing the trimmings, is a downwardly and forwardly inclined sheet metal chute 15 carried by the base of the machine. As shown in Fig. 4 the chute receives the trimmings x and directs them away from the trimming and stitching mechanisms.

Having thus set forth the nature of the invention, what I claim herein is:

1. An overedge sewing machine combining a frame, a work-supporting plate carried by said frame, overedge stitch-forming mechanism, a work-trimming mechanism, a work-feeding mechanism for feeding a workpiece to the trimming and stitch-forming mechanisms, a hem-folder located in advance of said stitch-forming and work-feeding mechanisms, means for supporting said hem-folder from said frame above said work-supporting plate, and an edge-guide supported from said frame below said work-supporting plate and arranged in spaced relation to said hem-folder, said edge-guide cooperating with the hem-folder to present to said mechanisms a workpiece having a marginal portion thereof folded in S-shape with the lower fold in the line of seam formation and with the projecting upper ply in the line of trimmer operation.

2. An overedge sewing machine combining a frame, a work-supporting plate carried by said frame, overedge stitch-forming mechanism including a reciprocating needle and a cooperating looper, a work-trimming mechanism, a work-feeding mechanism for feeding a workpiece to the trimming and stitch-forming mechanisms, a hem-folder, including a horizontally disposed substantially U-shaped work-folding member located in advance of said stitch-forming and work-feeding mechanisms, means including a vertically disposed supporting element connected to the upper arm of said member and to the upper part of said frame for supporting said member from said frame above said work-supporting plate, and an edge-guide located below and in spaced relation to said upper arm and supported from said frame below said work-supporting plate, said edge-guide cooperating with said member to present to said mechanisms a workpiece having a marginal portion thereof folded in S-shape with the lower fold in the line of needle penetration and with the projecting upper ply in the line of trimmer operation.

3. An overedge sewing machine combining a frame, a work-support carried by said frame, overedge stitch-forming mechanism, a work-feeding mechanism for feeding a workpiece to the

stitch-forming mechanism, a hem-folder located in advance of said stitch-forming and work-feeding mechanisms, means for supporting said hem-folder from said frame above said work-support and an edge-guide supported from said frame below said work-support, said hem-folder and its supporting means being located above said edge-guide and spaced therefrom, thereby affording an unobstructed passageway between the hem-folder and the edge-guide.

4. An overedge sewing machine combining a frame having a base portion and an upstanding portion, an overedge stitch-forming mechanism including a reciprocating needle and a cooperating looper, a work-feeding mechanism for feeding a workpiece to the stitch-forming mechanism, a hem-folder located in advance of said stitch-forming and work-feeding mechanisms, means for supporting said hem-folder from the upstanding portion of said frame, and an edge-guide supported from the base portion of said frame, said edge-guide cooperating with the hem-folder to present to said mechanisms a workpiece having a marginal portion thereof folded in S-shape with the lower fold in the line of needle penetration, said hem-folder and said edge-guide being so arranged relative to each other as to afford therebetween an unobstructed passageway for free passage of a workpiece.

5. An overedge sewing machine combining a frame, a work-support carried by said frame, overedge stitch-forming mechanism including a reciprocating needle and a cooperating looper, a work-trimming mechanism, a work-feeding mechanism for feeding a workpiece to the trimming and stitch-forming mechanisms, a hem-folder located in advance of said stitch-forming and work-feeding mechanisms, means for supporting said hem-folder from said frame above said work-support, an edge-guide supported from said frame below said work-support, the rear end portion of said edge-guide being formed with a rearwardly and downwardly inclined upper surface, said edge-guide cooperating with the hem-folder to present to said mechanisms a workpiece having a marginal portion thereof folded in S-shape with the lower fold in the line of needle penetration and with the projecting upper ply in the line of trimmer operation and with the marginal portion thereof overlying the inclined surface of said edge-guide, and a downwardly and forwardly inclined chute located rearwardly of said edge-guide for deflecting the marginal portion of the work trimmed off by said work-trimming mechanism.

6. An overedge sewing machine combining a frame, a work-supporting plate carried by said frame, overedge stitch-forming mechanism, a work-trimming mechanism, a work-feeding mechanism for feeding a workpiece to the trimming and stitch-forming mechanisms, a hem-folder located in advance of said stitch-forming and work-feeding mechanisms, means for supporting said hem-folder from said frame above said work-supporting plate, an edge-guide supported from said frame below said work-supporting plate, said edge-guide cooperating with the hem-folder to present to said mechanisms a workpiece having a marginal portion thereof folded in S-shape with the lower fold in the line of needle penetration and with the projecting upper ply in the line of trimmer operation, said hem-folder and its supporting means being located above said edge-guide and spaced vertically therefrom to afford an unobstructed passageway

therebetween, said edge-guide having transversely disposed downwardly inclined upper surfaces for permitting the marginal portion of said projecting upper ply to be deflected out of a horizontal plane, and a downwardly inclined chute for receiving and deflecting the marginal portion of the work trimmed off by the work-trimming mechanism.

7. An overedge sewing machine combining a frame having a base portion and an upstanding portion, overedge stitch-forming mechanism, a work-trimming mechanism, a work-feeding mechanism for feeding a workpiece to the trimming and stitch-forming mechanisms, a hem-folder located in advance of said stitch-forming and work-feeding mechanisms, means, including a stud fitted into the upstanding portion of said frame and a bracket supported by said stud and having the hem-folder connected thereto, for supporting the hem-folder from the upstanding portion of said frame, and an edge-guide supported upon the base portion of said frame, said edge-guide cooperating with the hem-folder to present to said mechanisms a workpiece having a marginal portion thereof folded in S-shape with the lower fold in the line of needle penetration and with the projecting upper ply in the line of trimmer operation.

8. An overedge sewing machine combining a frame having a base portion and an upstanding portion, overedge stitch-forming mechanism including a reciprocating needle and a cooperating looper, a work-trimming mechanism, a work-feeding mechanism for feeding a workpiece to the trimming and stitch-forming mechanisms, a hem-folder located in advance of said stitch-forming and work-feeding mechanisms, means, including a stud secured in the upstanding portion of the frame and a bracket supported on said stud and having the hem-folder connected thereto, for supporting said hem-folder from the upstanding portion of said frame, said stud being adjustable in the frame parallel to the line of feed and said bracket being adjustable on said stud transversely of the line of feed, means for holding said stud and bracket in their adjusted positions, and an edge-guide supported from said frame below said work-supporting plate, said edge-guide cooperating with the hem-folder to present to said mechanisms a workpiece having a marginal portion thereof folded in S-shape with the lower fold in the line of needle penetration and with the projecting upper ply in the line of trimmer operation.

9. An overedge sewing machine combining a frame, a work-support carried by said frame, overedge stitch-forming mechanism, a work-trimming mechanism, a work-feeding mechanism for feeding a workpiece to the trimming and stitch-forming mechanism, a hem-folder located in advance of said stitch-forming and work-feeding mechanisms and supported by said frame wholly above the plane of said work-support, and an edge-guide located at one side of said work-support and supported by said frame below said work-support, said edge-guide cooperating with the hem-folder to present to said mechanisms a workpiece having a marginal portion thereof folded in S-shape with the lower fold in the line of needle penetration and with the projecting upper ply in the line of trimmer operation.

10. An overedge sewing machine combining a frame having a base portion and an upstanding portion, overedge stitch-forming mechanism, a work-trimming mechanism, a work-feeding mechanism for feeding a workpiece to the trim-

ming and stitch-forming mechanisms, a hem-folder located in advance of said stitch-forming and work-feeding mechanisms and including a substantially U-shaped work-folding member, a carrier for said member, means for supporting said carrier comprising a stud secured in the upstanding portion of said frame, a U-shaped bracket having one leg thereof connected with said stud, said carrier being pivotally mounted between the legs of said bracket, and an edge-guide supported by the base portion of said frame, said edge-guide cooperating with the hem-folder to present to said mechanisms a workpiece having a marginal portion thereof folded in S-shape with the lower fold in the line of needle penetration and with the projecting upper ply in the line of trimmer operation.

11. In an overedge sewing machine having a frame, a work-supporting plate, stitch-forming mechanism, work-feeding mechanism and a work-trimming mechanism; a hemming attachment for hem-folding a workpiece and directing it to said mechanisms, comprising a hem-folder secured to said frame above the work-supporting plane of said plate and an edge-guide cooperating with said hem-folder secured to said frame below said plane and independently of the support for the hem-folder.

12. In an overedge sewing machine having a frame, a work-supporting plate, stitch-forming mechanism, work-feeding mechanism and a work-trimming mechanism; a hemming attachment for hem-folding a workpiece and directing it to said mechanisms comprising a hem-folding blade, a carrier to which said blade is secured, a supporting bracket on which said carrier is pivotally mounted, a stud secured in said frame above said carrier, means securing said bracket to said stud, an edge-guide cooperating with said hem-folding blade, and means securing said edge-guide to said frame below said work-supporting plate.

13. In an overedge sewing machine having a frame, a work-support, stitch-forming mechanism, work-feeding mechanism and a work-trimming mechanism; a hemming attachment for hem-folding a workpiece and directing it to said mechanisms comprising a hem-folding blade, a carrier to which said blade is secured, a vertically disposed supporting bracket having its upper end secured to said frame, means pivotally mounting said carrier on said bracket, means for adjusting said bracket horizontally in transverse directions, an edge-guide cooperating with said hem-folding blade, and means for supporting said edge-guide for horizontal floating movements.

14. In an overedge sewing machine having a frame, a work-support, stitch-forming mechanism, work-feeding mechanism and a work-trimming mechanism; a hemming attachment for hem-folding a workpiece and directing it to said mechanisms comprising a hem-folding blade, a carrier to which said blade is secured, a vertically disposed bracket having its upper end secured to said frame, means pivotally mounting said carrier on said bracket, means for limiting the pivotal movement of said carrier on said bracket, an edge-guide cooperating with said hem-folder, and means for supporting said edge-guide from said frame below and independently of said bracket.

15. In an overedge sewing machine having a frame, a horizontally disposed work-support, stitch-forming mechanism, work-feeding mech-

anism and a work-trimming mechanism; a hemming attachment for hem-folding a workpiece and directing it to said mechanisms comprising a vertically disposed bracket having its upper end secured to said frame above the level of said work-support, the lower end of said bracket being adapted to support any one of a plurality of carrier-blocks each fitted with a different form of hem-folding blade each of which is designed to form an S-shaped fold in the marginal portion of a workpiece, and an edge-guide supported on said frame below said work-support and cooperating with said hem-folding blades in directing the folded workpiece to said mechanisms.

16. In an overedge sewing machine having a frame, a work-support, stitch-forming mechanism, work-feeding mechanism and a work-trimming mechanism; a hemming attachment for hem-folding a workpiece and directing it to said mechanisms comprising a supporting bracket secured to said frame, a carrier pivotally secured to said bracket, a hem-folding blade pivotally mounted on said carrier on an axis parallel to the pivotal axis of said carrier, and an edge-guide supported by said frame and cooperating with said hem-folding blade.

17. In an overedge sewing machine having a frame, a work-support, stitch-forming mechanism, work-feeding mechanism and a work-trimming mechanism; a hemming attachment for hem-folding a workpiece and directing it to said mechanisms comprising a vertically disposed supporting bracket secured at its upper end to said frame, a carrier pivotally mounted on the lower portion of said bracket, means for limiting the pivotal movement of said carrier on said bracket, a hem-folding blade pivotally mounted on said carrier on an axis parallel to the pivotal axis of the carrier, and an edge-guide supported by said frame and cooperating with said hem-folding blade.

18. In an overedge sewing machine having a frame, a work-support, stitch-forming mechanism, work-feeding mechanism and a work-trimming mechanism; a hemming attachment for hem-folding a workpiece and directing it to said mechanisms comprising a vertically disposed supporting bracket secured at its upper end to said frame, a carrier pivotally mounted on the lower portion of said bracket, means for limiting the pivotal movement of said carrier on said bracket, a hem-folding blade pivotally mounted on said carrier on an axis parallel to the pivotal axis of the carrier, spring means normally tending to turn said hem-folding blade upwardly about its pivotal axis, and a manually releasable latch for holding said blade in its operative position in opposition to said spring means.

19. In an overedge sewing machine having a frame, a work-support, stitch-forming mechanism, work-feeding mechanism and a work-trimming mechanism; a hemming attachment for hem-folding a workpiece and directing it to said mechanisms comprising a vertically disposed supporting bracket secured at its upper end to said frame, a carrier pivotally mounted on the

lower portion of said bracket, means for limiting the pivotal movement of said carrier on said bracket, a hem-folding blade pivotally mounted on said carrier on an axis parallel to the pivotal axis of the carrier, spring means normally tending to turn said hem-folding blade upwardly about its pivotal axis, a latch for holding said blade in its operative position in opposition to said spring means, a latch-releasing lever mounted on said carrier and having a manually engageable portion projecting upwardly above the carrier, and an edge-guide supported by said frame and cooperating with said hem-folding blade.

20. In an overedge sewing machine having a frame, a work-support, stitch-forming mechanism, work-feeding mechanism and a work-trimming mechanism; a hemming attachment for hem-folding a workpiece and directing it to said mechanisms comprising a vertically disposed supporting bracket secured at its upper end to said frame, a carrier pivotally mounted on the lower portion of said bracket, means for limiting the pivotal movement of said carrier on said bracket, 25 a member pivotally mounted on said carrier and provided with a cam surface and a retaining notch, a hem-folding blade secured to said member, spring means acting on said member and normally tending to turn the member and the blade carried thereby upwardly about the pivotal axis of the member, a spring-pressed latch element mounted on said carrier and normally engaging said notch to hold said member and blade in their lowermost positions, and a finger-piece 30 mounted on said carrier and engaging said latch element to withdraw it from said notch to permit limited upward movement of said member under the influence of said spring means, said latch element reacting upon said cam surface, when said 35 finger-piece is released, to give to said member further upward movement.

21. In an overedge sewing machine having a frame, a work-support, stitch-forming mechanism, work-feeding mechanism and a work-trimming mechanism; a hemming attachment for hem-folding a workpiece and directing it to said mechanisms, comprising a hem-folder secured to said frame above the plane of said work-support, an edge-guide cooperating with said hem-folder 45 and secured to said frame below the plane of said work-support and means for adjusting said hem-folder horizontally in a plurality of directions relative to the line of seam formation.

NICHOLAUS KNAUS.
